(57) **CLAIM**

The ornamental design for an injection site tool, substantially as shown and described.

DESCRIPTION

FIG. 1 is a front view of an injection site tool according to a first embodiment depicted in a first position;

FIG. 2 is a left side view of the injection site tool of FIG. 1, the right side view being a mirror image thereof;

FIG. 3 is a top view of the injection site tool of FIG. 1;

FIG. 4 is a bottom view of the injection site tool of FIG. 1;

FIG. 5 is a front view of the injection site tool of FIG. 1 depicted in a second position;

FIG. 6 is a front view of the injection site tool of FIG. 1 depicted in a third position;

FIG. 7 is a front view of an injection site tool according to a second embodiment depicted in a first position, the side, top and bottom views being identical to those of the first embodiment;

FIG. 8 is front view of the injection site tool of FIG. 7 depicted in a second position;

FIG. 9 is a front view of the injection site tool of FIG. 7 depicted in a third position;

FIG. 10 is a front view of an injection site tool according to a third embodiment depicted in a first position, the side, top and bottom views being identical to those of the first embodiment;

FIG. 11 is a front view of the injection site tool of FIG. 10 depicted in a second position;

FIG. 12 is a front view of the injection site tool of FIG. 10 depicted in a third position;

FIG. 13 is a front view of an injection site tool according to a fourth embodiment depicted in a first position;

FIG. 14 is a left side view of the injection site tool of FIG. 13, the right side view being a mirror image thereof;

FIG. 15 is top view of the injection site tool of FIG. 13;

FIG. 16 is a bottom view of the injection site tool of FIG. 13;

FIG. 17 is a front view of the injection site tool of FIG. 13 depicted in a second position;

(Continued)

FIG. 18 is a front view of the injection site tool of FIG. 13 depicted in a third position;

FIG. 19 is a front view of an injection site tool according to a fifth embodiment depicted in a first position, the side, top and bottom views being identical to those of the fourth embodiment with the exception of the circle structure lines are dash-dot broken lines;

FIG. 20 is a front view of the injection site tool of FIG. 19 depicted in a second position; and,

FIG. 21 is a front view of the injection site tool of FIG. 19 depicted in a third position.

Portions of the article shown in dash-dot lines throughout the views of the fifth embodiment form no part of the claimed design.

The evenly spaced diagonal lines shown throughout the views of the first and second embodiments define contrasting surfaces.

The stipple shading shown throughout the views of first through fourth embodiments define contrasting surfaces.

The evenly spaced broken lines shown throughout the views of the second embodiment are part of the ornamental appearance of the second embodiment.
